United States Patent Office

Des. 232,411

Patented Aug. 20, 1974

232,411

CARAFE

Kenneth M. Douglas, Lake Delton, Gerald A. Rau, Baraboo, and Donald W. Doman, Janesville, Wis., assignors to Flambeau Products Corporation

Filed May 29, 1973, Ser. No. 364,558

Term of patent 14 years

Int. Cl. D7—01

U.S. Cl. D7—65

FIG.1

FIG.2

FIG.3

FIG.4

FIG.5

FIG. 1 is a top perspective view of a carafe showing our new design viewed from one side thereof;

FIG. 2 is a perspective view of the carafe of FIG. 1, viewed from another side thereof, with the lid open;

FIG. 3 is a side elevational view of the carafe of FIG. 1;

FIG. 4 is a top plan view of the carafe of FIG. 1; and FIG. 5 is a bottom plan view of the carafe of FIG. 1. We claim:

The ornamental design for a carafe, as shown.
